UNITED STATES PATENT OFFICE

2,491,762

AUTOMATIC AMPOULE SEALER

Andrew F. Piszel, North Arlington, N. J.

Application October 9, 1946, Serial No. 702,340

7 Claims. (Cl. 49—7)

1

This invention relates to improvements in automatic ampoule sealers.

An object of the invention is to provide an improved automatic ampoule sealer which will include a rotatable table top or drive disk formed with a plurality of spaced circumferentially disposed ampoule receiving openings and a synchronized ampoule tip pinching or sealing mechanism, together with means for automatically rotating the ampoules while their tips are being heated to a molten state immediately prior to the pinching or sealing operation.

Another object of the invention is to provide an improved automatic ampoule sealer having a driving motor and connected gear reduction mechanism for rotating a table top or drive disk formed with a plurality of spaced circumferentially disposed ampoule receiving openings and a synchronized ampoule tip pinching or sealing mechanism, together with means for automatically rotating the ampoules while their tips are being heated to a molten state by passing through the flame from a ribbon burner immediately prior to the pinching or sealing operation.

A further object of the invention is to provide an improved automatic ampoule sealer having a gear reduction driving means for operating a rotatable table top or drive disk formed with a plurality of spaced circumferentially disposed ampoule receiving openings and a synchronized ampoule tip pinching or sealing mechanism being radially and vertically adjustable with respect to said table top or drive disk for pinching or sealing various sizes of ampoules, together with means for automatically rotating the ampoules in their openings in said table top or drive disk while their tips are being heated to a molten state by passing through the flame from a ribbon burner immediately prior to the pinching or sealing operation, and means for automatically ejecting the ampoules from the openings in the table top or drive disk after the same have been sealed.

Another object of the invention is to provide an improved automatic ampoule sealing mechanism which will be highly efficient in operation, and relatively inexpensive to manufacture and produce.

Other objects will appear as the description proceeds.

2

In the accompanying drawings which form a part of this application,

Figure 1 is a top plan view partly broken away of the improved automatic ampoule sealer;

Figure 2 is a sectional view taken on the line 2—2 of Figure 1;

Figure 3 is a partial sectional view taken on the line 3—3 of Figure 2;

Figure 4 is a sectional view taken on the line 4—4 of Figure 1;

Figure 5 is a bottom plan view of a portion of the table top or drive disk; and,

Figure 6 is an enlarged detail view of a glass ampoule being sealed between the pinching or sealing rolls of the mechanism.

Like characters of reference are used throughout the following specification and the accompanying drawings to designate corresponding parts.

20 In carrying out the invention, there is provided a suitable flat table top generally denoted by the reference numeral 1 supported by the angle iron legs 2.

A circular opening 3 is formed through the 25 table top 1 and cooperates with the peripheral inwardly extending ampoule supporting ledge 4 disposed slightly below the level of the upper surface of said table top 1.

Angle irons 5 are disposed in spaced relation 30 below said table top 1 and are suitably attached to and supported by the angle iron legs 2, to support the motor supporting base plate 6 which is formed with an upwardly extending bearing flange 7 at one end thereof.

35 An electric driving motor 8 is mounted upon the base plate 6 adjacent the gear reduction mechanism 9, and the pulley 10 on the motor shaft 11 is connected with the pulley 12 on the shaft 13 extending from the gear reduction mechanism by means of the driving belt 14.

The gear reduction mechanism 9 is provided with a tapered drive shaft 15 upon which the rotatable ampoule supporting table top or drive disk 16 is fixed by means of the washers 17 and 45 nut 18, to extend flush with the table top 1.

A plurality of spaced circumferentially disposed ampoule receiving openings 19 are formed through the table top or drive disk 16, while an inset depending annular flange 20 is integrally formed 50 on the lower surface of said drive disk 16, with

its outer surface formed to provide a series of spaced vertical semi-circular seats or grooves 21 in which the ampules 22 will seat when inserted through the openings 19 in the drive disk 16 with their lower ends seating upon the supporting ledge 4.

The horizontal drive shaft 23 will extend outwardly from the gear reduction mechanism 9, passing through the bearing flange 7 and being further supported in the bearings 24 in the gear box or casing 25 supported by one of the angle irons 5. The worm gear 26 will be secured to the drive shaft 23, and will mesh with and drive the gear 27 fixed upon the elongated vertical drive shaft 28 which is rotatably mounted in the bearing 29 on the cover 30 for the gear box or casing 25, and in the bearing 31 at the bottom of said gear box or casing 25, the upper end of said shaft 28 extending through an opening 32 in the table top 1 to a point well above the surface of said table top 1.

A U-shaped bracket 33 is secured to the table top 1 with its side arms 34 and 35 extending horizontally and in spaced parallel relation. An adjusting screw 36 is formed with unthreaded ends which extend through the arms 34 and 35 to form bearing for said screw 36. The upper end of the screw 36 extends above the upper side arm 34 and supports the operating knob or handle 37, while a stop washer 38 is secured about the screw 36 below the arm 34 to prevent vertical movement thereof.

The U-shaped guide head 39 will be threaded upon the adjusting screw 36 to extend radially toward the center of the table top or drive disk 16 and will be adjusted vertically with respect to the table top 1 by rotation of the operating knob or handle 37 in the desired direction. The guide head 39 will be kept from rotation by means of the spaced vertical guide strips 40 and 41 positioned at the opposite sides of the bracket 33 and secured to said guide head 39 by means of the bolts 42 and 43.

A fixed block 44 will be disposed between the sides of the U-shaped guide head 39, and will be vertically apertured to receive the upper end of the vertical drive shaft 28 upon which said guide head moves when being vertically adjusted. A gear 45 is keyed to the shaft 28 above the block 44 and a stop washer 46 is secured about the shaft 28 below said block 44. The block 44 is slotted as at 47 to permit a lateral adjustment of the bolt 48 extending therethrough and the gear 49 which is supported thereon in meshing engagement with the gear 45.

Oppositely disposed guide slots 50 are formed in the inner surfaces of the sides of the U-shaped guide head 39, and slidably and adjustably support the tongues 51 on the opposite sides of the adjusting block 52. An adjusting screw 53 extends through the outer end of the guide head 39 and supports the operating knob or handle 54 on its outer end. A stop washer 55 is secured to the screw 53 on the inside of said guide head 39, while the inner end of said screw is threaded through said adjusting block 52, whereby rotation of said handle or knob 54 in one direction will advance the block 52 inwardly and rotation of the handle or knob 54 in the opposite direction will move the block 52 outwardly.

Cooperating tapered pinching or sealing rolls 56 and 57 are formed with the stems 58 and 59 which extend through the block 52, and support the intermeshing gears 60 and 61. Nuts 62 and 63 are threaded on the upper ends of the stems 58 and 59 for securing the rolls and gears in their

proper assembled relation, with the gear 61 meshing with the gear 49 supported by the block 44 and driven by the gear 45 on the vertical drive shaft 28.

From the foregoing description, it will be apparent that means have been devised for raising and lowering the pinching or sealing rolls and also for moving the same inwardly or outwardly in a radial direction with respect to the table top or drive disk 16 in which the ampules 22 are placed, thereby permitting ampules of various sizes to be sealed.

An arcuate ribbon burner 64 is formed with spaced apertures 65 through its inner wall to permit the flame to be directed inwardly upon the tips of the ampules 22 as they slowly pass therethrough to heat said tips to a molten state immediately before they pass between the pinching or sealing rolls. A pipe 66 is connected with a suitable source of gas supply (not shown) and to a Venturi mixer 67 which in turn is connected with the ribbon burner 64. An air inlet pipe 68 is also connected with the Venturi mixer 67, and valves 69 and 70 are provided for respectively controlling the amount of gas and air entering the Venturi mixer 67.

Brackets 71 are secured to the table top 1 for adjustably supporting the vertical rods 72, whose upper ends are formed into the bearing eyes 73 for longitudinally and adjustably supporting the rods 74 and 75 secured to said ribbon burner 64. Set screws 76 and 77 respectively hold or lock the rods 72 and 74 in the desired adjustment for directing the flame from the ribbon burner 64 upon the tips of various sizes of ampules.

The annular leather or rubber friction plate 78 is provided with the guide pins 79 and coil springs 80 disposed thereabout, with the friction plate positioned below the table top or drive disk 16 directly below said ribbon burner 64, whereby the sides of the ampules will be engaged by the friction plate 78 as the rotating drive disks bring them into contact with said friction plate to rotate the ampules as their tips are moved through the flame from the ribbon burner 64. The guide pins 79 extend through the vertical wall of the annular ampule supporting ledge 40. The ledge 4 is cut-out for a short distance as at 81 at a point adjacent to and beyond the ampule pinching or sealing rolls, so that the sealed ampules 22 may drop from the openings 19 in the table top or drive disk 16 and through said cut-out portion 81 into a basket or container (not shown) placed below said discharge or ejecting point.

From the foregoing description, it will be apparent that the mode of operation of the improved automatic ampule sealer will be as follows:

The electric motor 8 is put into operation by closing a circuit to a suitable source of electrical energy (not shown), and will drive the gear reduction mechanism 9, which in turn will slowly rotate the drive disk 16 in a counter-clockwise direction, and will also operate or drive the cooperating pinching or sealing rolls 56 so that when the ampules which have previously been filled are inserted in the openings at a point approximately opposite the pinching or sealing mechanism, the said ampules will be moved in a counter-clockwise direction until their side edges 70 are engaged by the friction plate 78 and at the same time, the tips of the ampules will be passed slowly through the flame from the ribbon burner 64. By the time that the ampules have been brought to the end of the ribbon burner, the tips 75 thereof will have been heated until they have

reached a molten state, whereupon they are immediately passed between the cooperating pinching or sealing rolls 56 and 57 which will pinch the tips together and seal the same. After the sealed ampoules 22 have passed in a counter-clockwise direction beyond the pinching or sealing mechanism, they will be brought to a point directly over the cut-out portion 81 in the ledge 4, and will drop therethrough from the openings 19 in the drive disk 16 into a suitable collecting basket or container (not shown).

It will be obvious that the heating means and that the friction plate may be adjusted radially with respect to the ampoules when placed in the drive disk 16, and also that the pinching or sealing rolls may be adjusted both vertically and radially with respect to said drive plate 16 to efficiently and effectively seal ampoules of various sizes.

From the foregoing description, it will be apparent that there has been devised a highly efficient form of automatic ampoule sealing mechanism.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention, what I claim as new and desire to secure by Letters Patent of the United States is:

1. An automatic ampoule sealing machine comprising a rotary multi-apertured plate for retaining and moving a group of individually retained and spaced ampoules in a predetermined path, an ampoule tip sealing mechanism disposed in close relation with the rotary plate, means for vertically and horizontally adjusting said tip sealing mechanism relative to the plate, a longitudinally and vertically adjustable burner tube disposed concentric to the plate and terminating at one side of the sealing mechanism said tube having spaced inner burner openings for heating the tips of the ampoules as they are moved toward the sealing mechanism, resiliently anchored friction means for successively engaging and individually rotating the ampoules so that the tips thereof are entirely subjected to the flames from the openings in the burner tube and means for simultaneously operating said rotary plate and sealing mechanism in synchronism.

2. An automatic ampoule sealing machine comprising a casing, having a circular opening in its top, a rotary drive disk having a plurality of spaced circumferentially disposed ampoule receiving openings formed therethrough mounted in said opening for moving a plurality of ampoules in a predetermined path, an ampoule tip sealing mechanism mounted on said casing in overlying relation with said disk and positioned in the path of travel of the ampoules, means for vertically and horizontally adjusting said sealing mechanism relative to the disk, an arcuate burner tube mounted on the top of said casing and disposed circumjacent to the disk and terminating at one side of the sealing mechanism, said tube being formed with a plurality of lateral openings on the inner wall thereof for heating the tips of the ampoules as they are moved toward the sealing mechanism, reciprocable friction means laterally disposed in the path of travel of the ampoules adjacent said burner tube for successively engaging the lower portion of each ampoule and ro-

tating the tip thereof so that the tips are entirely subjected to the melting action of the flames from the openings in the burner tube, means for simultaneously operating said rotary disk and sealing mechanism in synchronism and means for discharging the ampoules from the disk after passage through the sealing mechanism.

3. An automatic ampoule sealing machine comprising a casing, having a circular opening in the top thereof, a rotary drive disk, having a plurality of spaced circumferentially disposed ampoule receiving openings formed therethrough, mounted in said opening for moving a plurality of ampoules in a predetermined path of travel, an ampoule tip sealing mechanism mounted on said casing in overlying relation with the ampoule receiving openings in the disk and positioned in the path of travel of ampoules retained in the openings, means for vertically and horizontally adjusting said sealing mechanism relative to the disk, an arcuate burner unit mounted on the top of the casing and disposed concentric to the disk, said burner unit having a plurality of lateral openings directed toward and above the disk for heating the tips of the ampoules as they are moved toward the sealing mechanism, means for supporting said burner unit in adjusted vertical and longitudinal positions, resiliently anchored means laterally disposed in the path of travel of the ampoules for frictionally engaging the lower portion of each ampoule and successively rotating the ampoules to subject the entire portions of the tips thereof to the action of flames emanating from the openings in the burner unit, means for simultaneously operating said rotary disk and sealing mechanism in synchronism and means for discharging the ampoules from the disk after passage through the sealing mechanism.

4. An automatic ampoule sealing machine comprising a casing having a circular opening in the top thereof, a rotary drive disk, having a plurality of spaced circumferentially disposed ampoule receiving openings, mounted in said opening for moving a plurality of ampoules in a predetermined path of travel, a pair of vertically disposed complementary sealing rolls mounted on the casing and disposed in the path of travel of the ampoules, means for adjusting said rolls relative to the disk, a burner unit horizontally mounted in adjustable positions in the casing and disposed concentric to the disk, a resiliently biased member transversely fixed in the path of travel of the ampoules for frictionally engaging and individually rotating the ampoules so that the tips thereof are entirely subjected to the heating action of the burner unit and means for simultaneously and continuously rotating the disk and rolls in synchronism.

5. The combination of claim 2, wherein said adjusting means for the sealing mechanism includes a vertically disposed support mounted on the casing adjacent the opening, a vertical operating member journaled in said support, a horizontally disposed block, having a guide channel therein, carried by said operating member and an adjusting block slidably mounted in the channel, a pair of juxtaposed rolls depending from said adjusting block and cooperatively disposed in the path of travel of the ampoules.

6. The combination of claim 5, wherein said rolls are provided with gear ends in meshing engagement and rotatably mounted in the adjusting block, a drive shaft extending from said casing, a drive transmitting member carried by said shaft and operatively associated with said gear ends.

7. The combination of claim 2, wherein said

friction means includes a guide pin transversely extending from the casing into the path of travel of the ampules, a plate carried by said pin and resilient means disposed in engagement with said plate for projecting the same into the path of travel and enabling the plate to be withdrawn upon engagement thereby of the ampules.
